UNITED STATES PATENT OFFICE.

ALFRED JOHNSON, OF QUINCY, ILLINOIS.

INSULATOR.

No. 840,336.

Specification of Letters Patent.

Patented Jan. 1, 1907.

Application filed February 7, 1906. Serial No. 299,983.

To all whom it may concern:

Be it known that I, ALFRED JOHNSON, a citizen of the United States, residing at Quincy, in the county of Adams and State of Illinois, have invented new and useful Improvements in Insulators, of which the following is a specification.

This invention relates to insulators for holding and supporting electrical conductors, the object of the invention being to provide a simple, neat, and reliable insulator which will securely clamp and hold an electrical conductor or wire without bending or crimping the same or injuring the insulation on the wire, at the same time doing away with all tie-wires or the usual binding devices by which longitudinal slippage of the wire or conductor is prevented.

With the above and other objects in view the invention consists in the novel construction, combination, and arrangement of parts hereinafter more fully described, illustrated, and claimed.

In the accompanying drawings, Figure 1 is a sectional view of an insulator embodying the present invention extending transversely of the reversible seat block or step. Fig. 2 is a sectional view of the same, taken at right angles to Fig. 1. Fig. 3 is an outer face view of the base member of the insulator. Fig. 4 is an inner face view of the cap member or clamp. Fig. 5 is a detail perspective view of the reversible seat block or clamp. Fig. 6 is a face view of the rear side of the base.

The insulator contemplated in this invention comprises, essentially, a base 1, which is chambered out, as shown at 2, to receive the anchor-plate and seat-block hereinafter particularly described. This base may be cylindrical or of any other desired shape in cross-section, being, however, cylindrical under the preferred embodiment of this invention. Within the base 1 the latter is provided with a diametrically-disposed recess 3, in which is placed an anchor-plate 4 of suitable thickness, the same being provided with a hole to receive an attaching-screw 5, the head of which bears against the plate 4 and the shank of which extends through a corresponding opening in the back of the base 1 and beyond the same, so as to enter a side wall or ceiling or other support 6 for fastening the base to such support, as clearly shown in Figs. 1 and 2. The plate 4 is also provided at another point with a threaded hole 7, and in line therewith the base is formed with an opening

8, the said openings being intended to receive the inner threaded end of a clamping-screw 9, which holds the cap member of the device in place. The insulator also comprises a 60 clamping-cap 10, of porcelain or other non-conducting material, which corresponds in shape to the cross-sectional shape of the base 1 and is provided with an opening for the clamping screw-bolt 9, which passes therethrough, as shown in Fig. 1, and engages the anchoring-plate 4 for holding the clamping-cap firmly in place against the base. The base is further provided with a diametrical recess 11, extending entirely therethrough 70 and opening out at opposite sides thereof, and within said recess 11 is arranged a reversible four-sided seat block or step 12, made of porcelain or other non-conducting material, the length of which is approximately equal to the length of the recess 11. This seat-block is provided in each of its flat sides with a groove 13, and the several grooves 13 are of different sizes and depths to accommodate conductors or wires of different sizes and having different amounts of insulation. One or more of the grooves may be left perfectly smooth, as shown in Fig. 5, while the remaining grooves may be serrated or provided with transverse teeth 14, as 80 shown in the same figure, so as to obtain a firm grip on the wire in connection with the clamping-cap 10, which is provided in its inner face with a corresponding groove 15, either with or without transverse serrations 90 or teeth 16, as shown in Fig. 4. When the cap 10 is screwed firmly into place, the wire or electrical conductor shown at 17 is clamped firmly between said cap and the reversible seat block or step 12, and thus held 95 and prevented from slipping longitudinally, this being accomplished without bending or crimping the conductor or having to secure the same to the insulator by auxiliary ties of any kind.

The clamping-cap 10 is provided upon its inner side with an inwardly-projecting lug 18, through which a hole 19 is formed for the passage of the clamping screw-bolt 9. The lug 18 forms an interlocking projection which 105 rests in a notch or mortise 20, formed in opposite corners of the block 12. It is necessary to form the notches 20 only in diagonally opposite corners, for the reason that the block 12 may be turned end for end no 110 matter which groove 13 is presented to conductor-wire, so as to bring one of the notches

20 into position to be engaged by the stop-lug 18, which thereby acts to prevent longitudinal movement of the block 12 when subjected to excessive lengthwise strain. The 5 rear inner face of the base 1 is preferably provided with projecting spurs 21 to obtain a more positive grip or hold on the surface 6, to which the insulator as a whole is secured.

From the foregoing description it will be 10 seen that the base of the insulator is secured to its support independently of the clamping-cap and reversible seat-block, thus enabling the clamping-cap to be removed without displacing the base, and also enabling the seat 15 block or step to be removed and reversed end for end or turned over so as to present any desired groove for the reception of the conductor or wire. When the cap is returned to its place and firmly secured by means of the 20 bolt 9, the wire or conductor is firmly clamped between the cap and the block and held against movement in either direction.

I claim—

1. In an insulator, a base, means for securing said base to a suitable support, a reversible seat-block mounted in the base, and a clamping-cap lying opposite the seat block or step provided with means for securing the same to the base.
2. In an insulator, a channeled base, means for securing said base to a suitable support, a reversible seat-block mounted in the channeled portion of the base and provided with conductor-grooves in two or more faces thereof, and a clamping-cap having means for securing the same to the base and adapted to clamp the conductor against the seat-block.
3. In an insulator, a channeled base, an anchor-plate mounted therein, an attaching-

40 screw passing through the anchor-plate and base for securing the base to a suitable support, a seat for a conductor, a clamping-cap adapted to clamp the conductor against the seat or step, and a clamping-bolt passing through said cap and engaging a threaded 45 opening in the anchor-plate.

4. In an insulator, a channeled base, means for securing said base to a suitable support, a reversible seat-block mounted in the channeled base and removable therefrom, and a 50 clamping-cap having means for securing the same to the base, said cap being provided with a stop which engages the seat-block.

5. An insulator, a channeled base, means for securing said base to a suitable support, a 55 reversible seat-block removably fitted in the channeled base and provided with one or more notches, and a clamping-cap having means for securing the same to the base, said cap being provided with a lug which engages 60 one of the notches in the seat-block, substantially as and for the purpose described.

6. In an insulator, the combination with a base, and means for securing said base to a suitable support, of a reversible seat-block 65 having a plurality of faces provided with grooves of different sizes to receive a conductor, and a clamping-cap secured to the base and adapted to clamp said conductor within one of said grooves in the reversible 70 seat-block.

In testimony whereof I affix my signature in presence of two witnesses.

ALFRED JOHNSON.
